EXTENSION-TABLE.

No. 927,911.

Specification of Letters Patent.

Patented July 13, 1909.

Application filed September 3, 1908. Serial No. 451,490.

To all whom it may concern:

Be it known that I, ADDICK G. WETTERGREN, a citizen of the United States of America, residing at New York city, in the county 5 of New York and State of New York, have invented certain new and useful Improvements in Extension-Tables, of which the following is a specification, reference being had therein to the accompanying drawing.

10 This invention relates to an improvement in extension tables, the object thereof being to enable a small table to be more easily converted into one twice the size.

The invention consists essentially in the 15 means whereby the table covers are shifted and transposed in changing the table from one size to the other; and also it consists in the arrangement, construction and combination of parts substantially as will be herein- 20 after described and claimed.

In the annexed drawings, illustrating my 25 invention, Figure 1 is a top plan view of the main frame of my improved table with the top part removed. Fig. 2 is a longitudinal section of the same on the line 2, 2 of Fig. 1. Fig. 3 is a top plan view of the table when the parts are placed so that the table may occupy its extended position. Fig. 4 is a longitudinal section of the table when the 30 mechanism is in the position shown in Fig. 3. Fig. 5 is a cross section of the same.

Similar characters of reference designate like parts throughout all the different figures of the drawings.

35 The main frame of the table consists of a hollow rectangular body 1 of greater or less size. This main frame consists of the longitudinal sides 1^a, 1^a connected by the end pieces 1^b, 1^b. The upper edges of the sides 40 1^a are preferably provided with metallic plates 5 secured thereto by means of screws, while the end pieces 1^b which connect the sides 1^a have their upper edges preferably provided with metallic plates 6 at one end of 45 the table, and 7 at the other end (see Fig. 1).

The said main frame 1 is supported on the usual legs 2 which may be attached thereto in any desired manner and may have any suitable form and size. The main frame 1 is

50 normally covered by the table top 12 as shown in Fig. 2, which is a single flat piece. The common appearance of the unextended table is shown not only in Fig. 2 in full lines, but also in dotted lines in Fig. 1. Said top 12, however, is adapted to be slid endwise

for a certain distance when an extension of the table is to be effected, and then shifted to a position at right angles to that which it normally occupies when it covers the whole table, all as I shall presently explain. 60

3 denotes a horizontal bed or support which is substantially half the size of the rectangular frame 1 and is secured thereto, as shown in Fig. 1, near the plates 5 and 7, the other half of the rectangular frame 1 being left uncovered so that the extra leaf may be dropped therethrough into a boxing or upon a shelf placed within the frame 1 to receive it. 65

On the stationary bed 3 are secured parallel central rods 9 and 9^a, between which is a groove 8 designed to receive a sliding bar with which the table top 12 is provided. The rods 9 and 9^a are provided at one end with oppositely extending curved rods 10 and 10^a which together constitute right and left guide tracks which guide the pins 18 and hence the shiftable top 12 while being turned around crosswise, thus holding it securely in such adjustment. The rod 9 is furthermore 70 broken at the point 22 where it is formed with a curved and hooked extension 11. Opposite to this curved and hooked extension 11 of the rod 9, the rod 9^a is formed with an enlarged end having a curved edge 14. The 75 curved edge 14 corresponds in its curvature with the curved edge of the extension 11, and these two curved edges, namely that on the rod 9^a and that on the extension 11 of the rod 9, serve as tracks for pins or rollers 80 on the movable and adjustable table top 12. The rods 9 and 9^a may have any suitable width and shape, and their inner opposing edges preferably overlap the groove 8 to a small extent, as shown in dotted lines in 85 Fig. 1, so that the sliding bar which travels through the groove 8 may not escape through said groove, but may be held therein by the overlapping edges of the rods 9 and 9^a. Also, the edge of the curved track 10 and 10^a 90 similarly overlaps a small groove made beneath the same, as indicated in dotted lines, so that rollers or pins A on the table 12 may travel accurately in connection therewith. 95

The table top 12 is provided centrally with a short bar 15 pivoted thereto by means of a pivot 16. Said bar 15 has an enlarged lower part which spreads at the ends and sides of the bar 15 to form the flanges 19, as indicated in Figs. 1 and 2, which flanges operate 100 105 110

beneath the overlapping edges of the rods 9 and 9^a when the bar 15 is traveling through the guide groove 8. Furthermore, the table top 12 is provided with pins 18, 18, said pins 5 projecting from a plate 17 which is set into the top 12 opposite to the bar 15, the same pin 16 which serves as a pivot for the bar 15, passing likewise through the inset plate 17. The extended ends of the bar 15 overlap the 10 pins 18 when the bar 15 is in its central position, as indicated in Fig. 2. Thus it will be seen that when the bar 15 is traveling through the major part of its guide groove 8, the pins 18 will likewise be traveling in the 15 groove 8; but when the point is reached in said groove 8 where these pins 18 come opposite to the curved edges 14 and 11, the table top may be shifted on its pivot 16 and the pins 18 will pass to the opposite sides of the 20 groove 8, one moving through the groove 22 and along the curved edge 11, and the other moving along the curved edge 14, said movement continuing until one pin 18 strikes against the shoulder 14^a at the end of the 25 track 14, and the other pin 18 strikes against the shoulder 11^a at the hooked end of the curved edge 11. The table top 12 is furthermore provided with a pair of headed pins or rollers 20 which when the table top is in 30 its normal unextended position, as shown in Fig. 2, enter receiving notches 21, 21 in the plate 7 at one end of the frame 1. At the same time that these headed pins or rollers 20 enter the notches 21, a spring bolt 23 ar- 35 ranged in connection with the opposite end 1^b of the frame and working through the plate 6 engages a recess 24 in the table top 12, and thus the table top is kept firmly in position. When it is desired to shift the top 40 12 for the purpose of increasing the size of the table, the spring bolt 23 may be withdrawn from the top 12 by simply laying hold of the releasing catch 25, as shown in Figs. 1 and 2. The top 12 furthermore is provided 45 with a pair of headed pins or rollers 26, 26 which operate on the curved track 10, 10^a when the top 12 is being shifted from one position to the other.

Inside of the main frame 1, I place a horizontal tiltable leaf-receiving shelf 27 which is 50 preferably flanged at the edges, as at 30, and is designed to support the folding leaf which is used to enlarge the size of the table when it is to be extended. Said folding leaf is 55 designated 13, and when extended is of the same size as the permanent top 12. The leaf 13 is preferably hinged at the center so that it can be folded for the purpose of occupying as small a space as possible. It is 60 shown extended in Fig. 3 and folded in Fig. 2. It is placed upon the shelf by dropping it through the open part of the table frame, as I have already suggested, and it is easily removed from said open part when needed to 65 extend the size of the table. The inner op-

posing faces of the longitudinal sides 1^a, 1^a of the main frame 1 are provided with inclined grooves 28, 28, there being two on each of the sides 1^a, and the grooves at the opposite ends of the table being oppositely inclined to each other. The grooves at one end of the table are also somewhat longer than those at the other end, though this is a matter of taste and can be changed in different tables. The shelf 27 is provided with 75 lateral pins 29, two on each edge, which enter the grooves 28. It will thus be seen that the shelf 27 may occupy either the horizontal position shown in full lines in Fig. 2, or that shown in dotted lines in the same figure, and 80 that it is shiftable and tiltable by easily laying hold thereof, inasmuch as the lateral projecting pins 29 loosely engage the inclined grooves 28 and permit of such a movement. As the inclined grooves 28 which are 85 farthest from the open end of the table drop lower than the other or forward grooves, that is to say, as they come nearer to the lower edge of the sides 1^a, it is obvious that the shelf 27 will drop lower at that end than at 90 the forward end, when it is desired that it should do so. This is in order that the folded leaf 13, which is lying upon the shelf 27, may have one end thereof thrown upward into the 95 open part of the table frame where it can be more readily grasped by the hand for the purpose of removing it from its shelf and lifting it out of the frame for the purpose of placing it in position on the top of the latter.

I have stated that the inclined grooves 28 100 at one end of the table run lower down and nearer the bottom edges of the sides 1^a than do the similar grooves at the other end of the table. I may say also that the lateral pins 29 on the shelf 27 which coöperate with said 105 grooves that run nearest to the lower edge of the sides 1^a are set somewhat above the bottom of the shelf 27 and somewhat above the other pins which coöperate with the grooves 110 at the other end of the table. This is a detail of construction, however, to which I do not wish to be confined; although I realize that in actual practice the best results in the manipulation of the shelf are secured by this 115 placing of the pins; but I reserve the liberty of varying therefrom if desired.

When the permanent top 12 is in its unextended position, as shown in Fig. 2, the headed pins or rollers 26 will engage with the plates 5, as shown in Fig. 1, said plates projecting slightly over the edges of the sides 1^a on which they are secured, as indicated in dotted lines in Fig. 1, and hence when the table top 12 is moved in the direction of the arrow in Fig. 1, these headed pins or rollers 12 26, being underneath the overlapping edges of the plates 5, will assist in guiding the movement of the top and in keeping all the parts in proper relative position. The plates 5 are 13 provided with indent 34 where the headed

pins or rollers 26 can easily be disengaged from the plates 5 whenever the table is taken apart.

Supposing the top 12 to occupy the unextended position shown in Fig. 2, and that it is desired to extend the table, the first act will be to disengage bolt 23 from the top 12 by depressing the handle 25. The top 12 will then be pushed in the direction of the arrow in Fig. 1, which movement will result in disengaging the headed pins or rollers 20 from the notches 21, and in causing the bar 15 to slide through the groove 8 until the pin 18 stops by striking against the end of the table frame. At this time the top 12 can be shifted upon its pivot 16 which will cause the pins 18 to travel on the curved edges 11 and 14 as already explained. At the same time one of the rollers or headed pins 26 will pass out through the slot 31 cut in one of the plates 5, while the other headed pin or roller 26 will travel on the curved track 10^a toward the center of the table. In other words, the parts will assume the various positions shown in dotted lines at the left in Fig. 3, where the top 12 is in a position at right angles to that which it occupies in Fig. 2. The folded leaf 13 may now be withdrawn from the shelf 27 by tilting said shelf into the position shown in dotted lines in Fig. 20, as already explained. After the leaf has been unfolded, it will be placed upon the top of the table frame alongside of the top 12. In placing it the angle pins 33 on the underside of the leaf 13 will be caused to engage the overlapping edges of the plates 5 on the top of the frame, and likewise certain headed pins or rollers 35 on the underside of the leaf 13 will be caused to engage notches 32 in the plate 6, and also the bolt 23 may be caused to enter a suitable opening in the underside of the leaf 13. In this way the leaf 13 is held in position and the table top being extended by the use of this leaf in the manner I have explained will be twice as large as before. A reverse operation in the handling of the various parts may take place whenever it is desired to contract the size of the table to the normal, in which case the leaf 13 will be again folded and restored to its idle position on the shelf 27.

Having thus described my invention, what

I claim as new and desire to secure by Letters Patent, is:

1. In an extension table, the combination of a main frame provided with a guide-way 55 having right and left curved tracks at the end, and an attached shiftable table-top carrying a sliding bar having a centering pin and locking pins working in the guide-way and tracks respectively, and stop-devices 60 adapted to be engaged by said pins when the table-top is turned crosswise for the purpose of receiving an extra leaf.

2. In an extension table, the combination with a main frame provided with a straight 65 guide-way having right and left curved tracks at one end, a table-top having a sliding bar pivoted thereto and working in the guide-way and having also devices to engage the curved tracks, and an extension leaf provided with locking devices and adapted to be placed upon the frame after the table-top has been shifted into its crosswise position.

3. In an extension table, the combination with the main frame having oppositely inclined grooves on opposite inner faces of said frame, of a shiftable top arranged to leave an opening in the table when shifted, a leaf receiving shelf having lateral pins that engage said grooves so that the shelf may be 75 tilted and its contents lifted through said opening.

4. In an extension table, the combination with a main frame having central guiding tracks forming a straight guide groove and 85 provided with right and left curved tracks on opposite sides thereof at one end, and a shiftable table-top carrying a flanged sliding bar having a pivotal pin working in said guide groove, locking pin devices which engage the separate curved tracks, means for stopping the pin devices, and a folding leaf provided with connecting and retaining devices for removably attaching it to the main frame whereby the table-top surface can be 90 enlarged.

In testimony whereof I affix my signature in presence of two witnesses.

ADDICK G. WETTERGREEN.

Witnesses:

FRANK PAUL,
C. B. SCHROEDER.
